DESIGN FOR A TOY ANIMAL FIGURE

James L. Hvale, Chicago, Ill., assignor to Ekco Products Company, Chicago, Ill., a corporation of Illinois

Application May 27, 1946, Serial No. 130,117

Term of patent 3½ years

(Cl. D34—2)

To all whom it may concern:

Be it known that I, James L. Hvale, a citizen of the United States and residing at Chicago, in the county of Cook and State of Illinois, have invented a new, original, and ornamental Design for a Toy Animal Figure, of which the following is a specification, reference being had to the accompanying drawing, forming part thereof.

Fig. 1 is a front elevation of a toy animal figure, showing my new design.

Fig. 2 is a side perspective view of the same.

I claim:

The ornamental design for a toy animal figure, as shown.

JAMES L. HVALE.
